UNITED STATES PATENT OFFICE.

HERMANN FOLKES, OF BROOKLYN, NEW YORK.

EJECTOR FOR RECORDS.

1,418,555.

Specification of Letters Patent. Patented June 6, 1922.

Application filed July 19, 1921. Serial No. 485,876.

To all whom it may concern:

Be it known that I, HERMANN FOLKES, a citizen of the United States, and resident of borough of Brooklyn, county of Kings, State 5 of New York, have invented certain new and useful Improvements in Ejectors for Records.

The device the subject of this invention consists of a cabinet for retaining phonograph records and particularly to disc type 10 of record and for discharging or ejecting these records one at a time and in selected manner, from the cabinet.

It has been found that the possibility of 15 retaining records in a cabinet in the smallest space makes the records rather difficult of removal from the cabinet and in the past certain quite complicated devices have been employed for moving each record outward 20 so that it can be engaged by the fingers and totally removed from the cabinet, and in the past it has been expedient to provide an individual or independent ejecting means for each record. In my device will be found a 25 simple construction easy of operation and one operable with any record and with records of different diameter.

The following is what I consider the preferred means of carrying out the invention 30 and the accompanying drawings should be referred to for a complete understanding of the specification which follows:

In the drawings:

Figure 1 is a front elevation of a cabinet 35 showing records in place and my device in operating position.

Figure 2 is a sectional view through the cabinet showing my device in side elevation.

Similar reference numerals indicate like 40 parts in all the figures where they appear.

I have omitted the phonograph cabinet and the phonograph as well, as these parts or devices have nothing to do with the operation of my device, except that the cabinet 45 encloses my device and the records contained therein and the phonograph employs them. I confine myself therefor to the means for storing and retaining the records and for making them readily available.

50 The means for storing the records consists of a rack or cabinet that may be enclosed in the larger cabinet, a part of or the

support for the phonograph. This rack may be provided with side members 3 and 4 the top member 5 and bottom member 6 which 55 may be of wood and of any size or design as shall be required or found expedient.

Spaced from the top 5 is a bar or shelf 7 extending the full width of the cabinet and arranged transversely on this bar is a plurality of cleats 8 parallel with each other and preferably continuous across the bar or shelf 7.

Secured to the shelf 7 is an angularly disposed extension 9 extending the full length 65 of the shelf 7 and also provided with cleats 10 arranged parallel with each other and coinciding in alignment with the cleats 8 above referred to and a downward extension or lip 11 secured to the member 9 is provided with 70 a felt bumper 12 against which the periphery or outer edge of the discs may rest.

Upon the bottom of the cabinet as shown at the right in Figure 1, I arrange a plurality of cleats 13 parallel with the cleats 8 and 75 with each other and so positioned that a disc record 14 when placed therebetween will be retained in a vertical position resting with its edge between pairs of cleats 8, 10 and 13 and against the bumper 12. The records 14 80 are of a large size. I may also provide to retain records 15 of a smaller diameter within the same cabinet and while I prefer that the upper edge of all records in the cabinet should be upon the same plane I may provide 85 a shelf 16 having a support 17 upon which I secure cleats 18 which serve as do the cleats 13 in retaining the lower edges of records in this instance the smaller records 15.

When a plurality of records is arranged 90 as shown and described, the forward edges of all of the larger records and the forward edges of all of the smaller records would coincide and the spacing between records is such that the fingers cannot be introduced 95 to a sufficient extent to grasp the edge of the record. I have therefore provided means for moving individual records outward. The means consists of a bar 19 the inner end of which is turned downward and 100 provided with a slot 20 adapted to engage the edge of a record. The bar continues through the thimble member 21 and terminates in a plate, handle or knob 22. I place

a spring 23 upon the bar with one end resting against a disc 24, adjacent or secured to the thimble member 21 and the other end secured to the bar or resting upon a pin 5 25 extending through the bar.

Now, when the handle member 22 is pulled outward the recess 20 will engage a record and move it outward and when the handle 22 is released the bar 19 and handle and slot 10 20 will return to the position shown.

Upon the shelf 7 a plurality of numbers are shown, these are index numbers and the pointer 26 secured to the bar 19 adjacent to the handle 22 and movable with the bar is 15 free to pass over the index 27 and will indicate the number of the record to be moved. It is necessary to retain the thimble 21 and to cause the bar to pass freely above the records, to accomplish this I provide a rod 20 28 secured to the shelf 7 by any suitable means and extending the full length of the shelf 7 and into the sides 3 and 4 of the rack and secured to or formed integral with the thimble 21 is a traveler 29, a cylindrical or 25 tubular member having one side cut away. This member engages the rod 28 and is free to move thereon and it will be noted that a small portion of the sides 3 and 4 are removed as shown at 30 to allow the traveler 30 29 to project therethrough so that records arranged close to the sides 3 and 4 may be engaged by the bar 19.

In the index 27, the numbers may be arranged in any way desirable or letters or 35 other indicating marks may be employed.

The rack may be arranged and adapted for records of the same diameter or one rack and ejecting means may be arranged above the other and other modifications may be 40 made within the scope of the appended claims without departing from the principle

or sacrificing the advantages of the invention.

Having described my invention what I claim is:

1. An ejector for record cabinets comprising a rod, an open thimble slidable upon said rod, a thimble transverse of and secured to said first mentioned thimble, a rod passing through said second thimble and 50 having its inner end curved and recessed and a spring upon said rod and adapted to be compressed when said rod is moved outward.

2. The combination with a cabinet having 55 a partition therein and means upon said partition for retaining records, of a guide rod secured to said partition at the side opposite said records, a sleeve movable upon said guide rod a second sleeve of box section and 60 secured to and transverse of said first sleeve, a movable ejector rod extending through said second sleeve and having one end curved and the other end provided with a finger engaging means for moving said ejector rod 65 in one direction and a spring upon said rod and secured thereto for moving the rod in the opposite direction.

3. A record cabinet and ejector therefor comprising a shelf in said cabinet and having an angularly disposed projection therefrom, a rod extending transverse to said shelf and having one end bent over and beyond said projection, a rod secured upon said shelf and extending longitudinally 75 thereof a thimble upon said rod, and having one side open, and a guide thimble upon said first rod and secured to the first mentioned thimble, and means for operating said first mentioned rod through said guide 80 thimble.

HERMANN FOLKES.
